(57) **CLAIM**

The ornamental design of a rotating and self-supporting media player, as shown and described.

DESCRIPTION

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.

FIG. 1 is a perspective view of a rotating and self-supporting media player showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view thereof, shown in rotated position and bottom supports in extended position; and,

FIG. 9 is front elevational view of FIG. 8 in an alternate position.

The broken line showings throughout the views are for illustrative purpose only and form no part of the claimed design. The broken lines, which define the bounds of the claimed design, form no part thereof.
